UNITED STATES PATENT OFFICE.

LEONARD R. STEEL, OF CHICAGO, ILLINOIS.

SHIPPING-CAN.

1,148,059.

Specification of Letters Patent. Patented July 27, 1915.

Application filed October 25, 1913. Serial No. 797,290.

To all whom it may concern:

Be it known that I, LEONARD R. STEEL, a citizen of the United States, residing at Chicago, in the county of Cook and State of Illinois, have invented new and useful Improvements in Shipping-Cans, of which the following is a specification.

This invention relates to shipping cans; and it has for its primary object the provision of a structure of this character which will effectually serve to retain the contents of the can at a practically uniform temperature for a considerable period of time.

Another object of the invention is the provision of a structure of this character which will include an outer vessel of separable sections, an inner vessel removably fitted in the outer vessel, and an intermediate lining of insulating material between the inner and outer vessels and arranged to wholly embrace or completely jacket the inner vessel to protect the same from the outside air.

Another object of the invention is the provision of a structure of this character which will be formed of separable sections that are adapted to be readily separated as the occasion may demand and treated to a sterilizing bath and maintained in a highly sanitary condition.

A further object of the invention is the provision of a can including an outer sectional vessel having a removable cover and an inner lining of insulated material associated with the walls of the outer vessel in such manner as will prevent certain sections of the lining from separating when the structure is canted.

A further object of the invention is the provision of a structure of this character which will include an outer vessel of separable sections and a cover section and means between the separable sections and the cover section for sealing the latter to prevent tampering with the contents of the can without detection.

With these and other objects in view, the invention consists of certain novel features of construction, combination and arrangement of parts, as will be hereinafter described and claimed.

In the accompanying drawings:—Figure 1 is a side view of the can; Fig. 2 is a vertical section therethrough; Fig. 3 is a horizontal section taken on the line 3—3 of Fig. 2; Fig. 4 is a perspective view on a reduced

scale of the annulus of the lower section of the outer vessel; and Fig. 5 is a perspective view of the annulus of the breast section of the outer section.

The can as designed is particularly intended for the shipment of milk or the storage of liquids that must be held at a certain temperature for a predetermined period of time, and as illustrated the can has comprised in its construction an outer vessel 1 having a lower substantially cylindrical section 2, an upper breast section 3 and a closure section 4. The lower section 2 is closed by a bottom member 5, which is disposed above the lower edges of said lower member and provided with a depending outer flange 6, which is embraced by the lower walls of said section 2. Embracing the lower walls of the section 2 and secured thereto and to the flange 6 by means of rivets 7 is a reinforcing ring 8 formed preferably of flat sheet metal and designed to coöperate in the purpose of the flange 6 to sufficiently strengthen the bottom of the can and prevent the same from being injured while in transit.

At the upper end the section 2 is embraced by an annulus 9 riveted to said section, as at 10, and then offset at 11 to overlie the upper edge of said section and then terminally formed to provide a vertical annular flange 11, the latter having diametrically-disposed fixed threaded studs 12 provided at their outer ends with stop projections 14. The breast section 3 has riveted thereto, as at 15, an annulus 16 having diametrically-disposed bayonet slots 17 whose vertical branches 18 are adapted to initially receive the studs 12, while the horizontal branches 19 of said slots are adapted to subsequently receive the studs 20 when the breast section is rotated, slightly upon the lower section 2. After the sections 2 and 3 have been rotated relatively for the purpose just mentioned, adjusting nuts 20 on the studs may be brought to bear against the annulus 16, and, as a consequence thereof, the studs will be held against accidentally working into the vertical branches 18 of said bayonet slots 17, and the sections 2 and 3 held operatively connected with each other.

The breast section 3 is of cylindrical form at its base and from the base said section is gradually curved inwardly at 21 and finally the walls of the section are extended into a

vertical flange 22. This flange is embraced by the depending flange 23 of a closure section 24, the latter having a crown 25 which forms a seal to completely cover the inner vessel 26.

The inner vessel 26 may be constructed of glass, porcelain, metal lined with porcelain or any other suitable well known material, and it is preferably provided with a cylindrical body 27 whose walls are merged into a curved breast 28. The walls of the breast 28 lie parallel with the curved walls 21 forming the breast of the section 3 of the outer vessel. The walls of the breast 28 are extended into the vertical neck 29 which terminates slightly beyond the outer edge of the flange 22 of the outer vessel in order that the contents of the inner vessel may be poured from the can without said flange 22 forming an obstruction. The neck 29 of said inner vessel is exteriorly threaded at 30 to receive a correspondingly threaded flange 31 of a closure 32. This closure carries a fixed handle 33 which is adapted to be grasped by the hand and manipulated in order to effect adjustment of the closure onto or off of the neck 29, as will be understood. In order to prevent the liquid within the vessel 26 from contacting with the metal of the closure 32, I preferably provide the latter with an inner disk 34.

Interposed between the inner vessel 26 and the outer vessel 1 is a lining of insulating material which consists of a base section 34' having a bottom 35 interposed between the bottom 5 of the outer vessel and the bottom 36 of the inner vessel and at a point below the upper end of the section 2 of the outer vessel the said section 34' of the insulated lining is provided with a stepped portion 37, which fits a correspondingly stepped portion 38 of an upper breast section 39 of the lining. It is preferred that the upper end of the section 34' of the lining terminates below the upper end of the section 2 of the outer vessel in order that the walls of the section 39 of the lining will lap the joint between the sections 2 and 3 of the outer vessel and thereby minimize the possibility of the outside air entering within the lining, as will be understood. The breast section 39 terminates in a short vertical flange 40 which embraces the neck 29 of the inner vessel, and which is preferably spaced therefrom. Said flange 40 terminates below the outer end of the neck 29 so that the latter will be exposed sufficiently therebeyond to permit the contents of the inner vessel to be poured without said flange 40 forming an obstruction. The insulated lining is completed by a closure section 41 of insulating material having a flange 42 which extends around the neck of the inner vessel and which embraces the flange 40 of the breast section 39 of the lining. Said

flange 42 is provided with a beveled lower surface 43 which is adapted to rest against the adjacent outer surface 44 of the breast section.

In order to prevent the contents of the inner vessel 26 from being removed from the can without detection, I provide the studs 12 with passages 45, while the flange 23 of the closure 4 is provided with staples 46 that are arranged to mate with the passages 45 and to receive therewith suitable sealing wires 47. In this manner, it is seen that if the cover 4 is rotated on the outer vessel, said sealing wires will be broken. The cover 4 is provided with an opening 48, in which one end of a chain 49 is connected, the opposite end of the chain having connection with one side of the breast section 3 of the outer vessel, as at 50. In this manner loss of the cover 4 from the section 3 is prevented.

The closure section 41 is provided at its lower end with an exteriorly arranged reduced portion 42' adapted to receive the vertical upstanding flange 22 of the breast section of the outer vessel. It will be noted that by this arrangement, the vertically extending flange 22 is substantially flush with the periphery of the section 41, thereby preventing any bulging effect of the flange closure 4 when in active position. 95

From the construction described, it is seen that in filling the inner vessel 26 the cover 4 of the outer vessel may be removed together with the cover section 41 of the lining so as to fully expose the neck end of said inner vessel. Said neck end preferably has a relatively large internal diameter so that the liquid may be freely poured into the vessel without accidentally spilling from the sides thereof. After the inner vessel is filled, the insulated closer section 41 is placed on the mating breast section 39 and securely fitted thereto so as to minimize the possibility of the air entering the joints between both sections. The section 4 of the outer vessel is then connected with the section 3 and locked thereto by the sealing wires previously described. When desired, the breast section 3 of the outer section may be removed from the section 2, so as to expose the breast section 39 of the insulated lining and permit said section and the bottom section 34 to be entirely removed and treated to a sterilizing bath.

Incident to the fact that the breast 21 is curved as described and that the breast 28 is arranged with its walls parallel with the walls of the breast 29, the section 39 of the lining will be held against movement in an outward direction when the structure is canted to pour the contents from the inner vessel. At diametrically opposite sides the breast section 3 of the outer vessel is provided with suitable hand grips or handles 51. 180

The openings 45 are disposed outwardly of the adjusting nuts 20 when the sealing wires are connected between the studs and the closure 4, and, as a consequence of this arrangement, the nuts 20 are held against adjustment in an outward direction.

I claim:—

1. A shipping can comprising an outer vessel, an inner vessel, a sectional lining of insulated material interposed between the inner and outer vessels; a closure for the inner vessel, a closure for the outer vessel, and a closure of insulated material fitting one of the lining sections and interposed between the closure of the outer vessel and the closure of the inner vessel.

2. A shipping can comprising an outer vessel, an inner vessel, a sectional lining of insulated material interposed between the inner and outer vessels, a closure for the inner vessel, a closure for the outer vessel, and a closure of insulated material fitting one of the lining sections and interposed between the closure of the outer vessel and the closure of the inner vessel and separable therefrom.

3. A can comprising an outer vessel, an inner vessel having a neck extending beyond one end of the outer vessel, a sectional lining of insulating material interposed between the inner and outer vessels and terminating below the outer end of the neck of the inner vessel, a closure fitting the neck of the inner vessel, a closure for the outer vessel and a closure interposed between the closure of the inner vessel and the closure

of the outer vessel and removably fitting the adjacent end of the lining.

4. A shipping can comprising an outer vessel, an inner vessel, a sectional lining of insulated material interposed between the inner and outer vessels, a closure for the inner vessel, a closure for the outer vessel, and a flanged closure of insulated material having a beveled lower edge fitting one of the lining sections and interposed between the closure of the outer vessel and the closure of the inner vessel, the beveled flange of the last named closure engaging the outer surface of said lining.

5. A shipping can comprising an outer vessel curved inwardly to provide a vertical flange, a lining of insulated material interposed between the inner and outer vessels, a closure for the inner vessel, a closure for the outer vessel provided with a flange adapted to embrace the flange of the outer vessel and having a beveled lower edge adapted to contact with the inwardly curved portion of said outer vessel, a flanged closure for the lining provided exteriorly with a reduced portion for the reception of the flange of the outer vessel, thereby establishing an air tight joint between the inner and outer vessel.

In testimony whereof I affix my signature in presence of two witnesses.
